DESIGN FOR A MUSICAL STRING TOY

Philip A. Mosco, Elmhurst, Long Island, N. Y.

Application May 22, 1946, Serial No. 129,980

Term of patent 7 years

(Cl. D34—15)

To all whom it may concern:

Be it known that I, Philip A. Mosco, a citizen of the United States, residing at Elmhurst, Long Island, in the county of Queens and State of New York, have invented a new, original, and ornamental Design for a Musical String Toy, of which the following is a specification, reference being had to the accompanying drawing, forming a part thereof.

In the drawing:

Fig. 1 is a perspective view of a musical string toy showing my new design;

Fig. 2 is a top plan view; and

Fig. 3 is a side elevational view of the same.

I claim:

The ornamental design for a musical string toy, as shown.

PHILIP A. MOSCO.
